UNITED STATES PATENT OFFICE

2,469,292

DRINKING TUBE HOLDER

Catherine B. Cornwell, Belmont, Calif.

Application August 27, 1945, Serial No. 612,925

1 Claim. (Cl. 65—65)

1

This invention relates to a tube retaining device and has particular reference to means associated with a drinking glass or tumbler for positioning and retaining therein against danger of accidental displacement a drinking tube through which the liquid content of the glass is conveyed to the mouth.

The principal object of the invention is the provision of a resilient member that is readily adjustable over glasses of varying diameters and the provision with said member that encircles the glass of a pivoted drinking tube retaining element, that in the preferred form of the invention can be arranged into a compact form when not in use.

An additional object of the invention is the production, in a modified form of the invention, of a clamp element associated with the glass encircling member, which clamp is capable of being positioned beneath the base of the glass to assure a further positive retention of the tube within the glass and to avoid the possibility of displacement of the glass encircling member.

A further object of the invention is the provision of a device of the character described that is simple in construction, economical to manufacture, positive in operation, strong, durable and highly efficient in use.

Other objects and advantages will be apparent during the course of the following description:

In the accompanying drawing forming a part of this specification and in which like numerals are employed to designate like parts throughout the same,

Fig. 1 is a perspective view of a glass having my invention associated therewith,

Fig. 2 is a rear elevation of a modified form of the invention in which an auxiliary clamp is associated with the glass encircling members, and

Fig. 3 is an edge elevation of the same, the glass being shown in section.

Invalids in hospitals and in homes when confined to bed, experience great difficulty in retaining a liquid holding glass in one hand and the conventional drinking tube in the other. Furthermore, the tube frequently falls from the glass when the tube is being used by the invalid or when the glass is being conveyed to the invalid by the nurse or other attendants. The dropping of the tube to the floor either while being used by or being conveyed to a patient, often results in a loss of a tube, or a breaking of a tube, or if the tube falls intact it is frequently crushed when stepped upon, resulting

2

in a dangerous, unsightly and unsanitary condition, particularly in a hospital. To therefore provide a medium to prevent accidental displacement of the tube from the glass, and to thus overcome the above recited annoyances and inconveniences, I have devised the present invention.

In the accompanying drawing wherein for the purpose of illustration is shown the preferred embodiment of my invention, the numeral 4 designates a glass or tumbler that is provided adjacent its mouth portion with a circumferential flared portion 5. An expansible circular member 6 having the form of a helical spring encircles the glass directly beneath the flared portion 5, the flared portion preventing a riding of the member to the top of the glass. It will be noted that the said expansible member 6 is equipped with hook ends 7 and 7' that are receivable in openings 8 and 9, respectively, formed in the reduced extremities of a pin 10. This pin is solid throughout the greater portion of its length and is so constructed and arranged relative to the hook ends 7 and 7' that it has a dual function. It not only serves to connect the ends of the member 6 to provide a continuous glass encircling medium, but, as illustrated to advantage in Fig. 1, also serves to receive and pivotally retain thereon the upwardly bent clamping end 11 of a metal strip 12. The said strip it will be noted is provided with an enlarged head 13 having an opening 14 therein.

A drinking tube 15 of conventional form is disclosed as passing through the opening 14 and will be partially immersed in any liquid contained in the glass with the upper end of the tube being readily accessible so that the liquid can be drawn to the mouth of the user.

In the modified form of the invention disclosed to advantage in Figs. 2 and 3 instead of employing a single strip 12, I utilize an auxiliary clamping element that is designated as a whole by the numeral 16, which clamping element is provided at its upper end with a pair of ears 17 and at its lower end with a base 18 formed at right angles to the body of the clamp and underlies the bottom of the glass. It will be noted that the ears of the auxiliary clamp encircle the pin 10 and thus provide a pivotal mounting of the clamp on said pin so that the base 18 may be readily positioned beneath the bottom of the glass. In this instance the bent end 11 of the strip 12 is pivotally mounted between the space ears 17 and is free to move therebetween. When the device is used on glasses that have non-

flaring sides, this auxiliary clamp 16 and the base 18 cooperate with the glass encircling and gripping member 6 to produce a type of mounting for the drinking tube that assures a retention of the latter within the glass.

In applying the device the glass is first encircled by the expandable member of ring 6 and the inherent resiliency of the same, whether a spring or an elastic band be employed, will cause a snug fitting of said member about the glass. The said strip 12 is then moved on its pivot to assume the inclined position illustrated in Fig. 1. Thereafter the tube is trained through the opening 14 of the strip and downward pressure on the tube will cause the lower end of the tube to contact the side and bottom of the glass. When thus positioned the upper end of the tube will be readily accessible to the user to draw the liquid from the glass. It will be obvious that pressure of the lower end of the tube against the side and base of the glass and the angular position of the strip relative to the mouth of the glass will prevent accidental displacement of the tube.

It is to be understood that the forms of my invention herewith shown and described are to be taken as preferred examples of the same and that various changes relative to the material, size, shape and arrangement of parts may be resorted to without departing from the spirit of the invention or the scope of the subjoined claim.

Having thus described my invention, I claim:

30

A device for retaining a drinking tube within

a glass, comprising an elastic ring-shaped member compressible about the body of the glass, said member having hook ends, a cross pin having openings in the extremities thereof for receiving the hook ends of said compressible member, an elongated strip pivotally connected at its lower end to said pin, said strip having an opening in its upper end for receiving the drinking tube therein, an auxiliary clamp having a bottom portion positioned beneath the base of the glass, and spaced apertured ears formed on the upper end of said clamp capable of encompassing said pin and defining a pivotal mounting for the upper end of said clamp about said pin.
